UNITED STATES PATENT OFFICE.

ESTHER ROSENBLUM, OF LOS ANGELES, CALIFORNIA.

FOUNTAIN TOOTH-BRUSH.

1,168,965.

Specification of Letters Patent. Patented Jan. 18, 1916.

Application filed May 5, 1915. Serial No. 25,952.

To all whom it may concern:

Be it known that I, ESTHER ROSENBLUM, a citizen of the United States, residing at Los Angeles, in the county of Los Angeles and State of California, have invented a new and useful Improvement in Fountain Tooth-Brushes, of which the following is a specification.

The object of this invention is to provide a tooth brush adapted to contain a liquid tooth paste or the like within the handle and to provide means for supplying a limited amount of this liquid to the bristles of the brush when desired, and my invention consists of the novel features herein shown described and claimed.

The accompanying drawings illustrate the invention.

Figure 1 is a side elevation of my fountain tooth brush. Fig. 2 is an enlarged vertical fragmentary sectional detail, taken upon the line 2--2 of Fig. 3. Fig. 3 is an enlarged cross section taken upon the lines 3--3 of Figs. 1 and 2.

Referring more particularly to the drawings, 1 in a general way indicates the handle of a tooth brush constructed in accordance with my invention, said handle being cylindrical and provided with a head 2 for the reception of the ordinary bristles 3. The handle 1 and head 2 are preferably formed integral and consist of metal or any other convenient material. A longitudinal bore 4 extends through said head and handle and is internally screw threaded at the head end for the reception of an exteriorly threaded plug 5. The head 2 is semi-cylindrical in cross section and the under side thereof is flat and provided with a series of small vertical ports 6.

A valve in the form of a resilient flat spring 7 covers the ports 6 and is held in operative position by screws 8. A thin gasket 9 of cork or other similar material is interposed between the spring 7 and the inner face of the head 2 to secure a tight fit between these parts. The spring 7 extends inwardly a distance and is provided with a slot 10 for the reception of a valve stem 11, said stem extending transversely of the bore 4 and outwardly through an opening 12 in the handle 1. The outer end of 13 of said stem being larger in diameter and forming

a push button 14. An annular groove 15 is formed around said push button for the reception of a washer or gasket 16, said gasket preventing any leakage from the bore 4 through the opening 12. The upper end of the stem 11 is provided with a small valve head 17 adapted to be normally seated in a valve seat 18 in the casing 1.

The tendency of spring 7 is to remain normally seated upon the gasket 9 and to hold the air valve 17 seated in its seat 18 and the push button outwardly in position 65 to be manipulated by the operator.

It is obvious that when the push button is operated the valve 7 is unseated thereby allowing the desired amount of liquid to escape through the ports 6 into the bristles 70 3, and the air valve is simultaneously unseated to allow a slight amount of air to enter the chamber or bore 4 to facilitate the operation.

When it is desired to charge the brush, 75 the cap 5 is unscrewed and liquid is inserted into the bore 4.

It is obvious that many changes may be made in the details of construction as set up in the following claim.

What I claim and desire to secure by Letters Patent of the United States is:

A fountain tooth brush comprising a cylindrical handle, a semi-cylindrical head formed integral with said handle and provided with bristles, a longitudinal bore extending through said handle and head, ports extending outwardly from the bore in the head to the bristles, a valve in the form of a flat spring adapted to normally close 80 said ports, a slot formed in the outer end of said valve, a gasket between the valve and ports, a valve stem extending transversely of said bore and having an air valve upon the upper end thereof, a shoulder upon said stem, one end of said stem extending through an opening in the underside of the handle, a gasket upon said stem fitting in 85 said opening, and the slot formed in said first mentioned valve operatively engaging 90 the shoulder upon said stem to simultaneously open said valves.

ESTHER ROSENBLUM.
